UNITED STATES PATENT OFFICE.

BENJAMIN F. GEYER, OF FORT WAYNE, INDIANA, ASSIGNOR TO WAYNE OIL TANK AND PUMP COMPANY, OF FORT WAYNE, INDIANA, A CORPORATION OF INDIANA.

QUANTITY STOP MECHANISM FOR MEASURING PUMPS.

Application filed September 27, 1921. Serial No. 503,638.

To all whom it may concern:

Be it known that I, BENJAMIN F. GEYER, a citizen of the United States, residing at Fort Wayne, in the county of Allen and 5 State of Indiana, have invented new and useful Improvements in Quantity Stop Mechanism for Measuring Pumps, of which the following is a specification.

My improvements relate to measuring 10 pumps such as those used for gasoline; and particularly to the means for limiting the movement of the pump piston to ensure discharge of the quantity of liquid desired.

The invention consists of a new combination 15 of rod and stops thereon; and is characterized by few and simple parts, and ease of manipulation.

My invention is illustrated in the accompanying drawing in which;

20 Figure 1, is an elevation of the device and the lower portion of rack fixed to the piston-rod, together with the projection carried by the rack. The stop-rod is shown broken to shorten same; the lowest stop is 25 shown side view or contact position, when one gallon is to be delivered; the second stop is shown back view; the third stop is shown front view and the fourth or top stop is shown in vertical axial section from 30 front to back,

Fig. 2, is a cross section on the line 2—2 of Figure 1, as tho the rack was there shown in full,

Fig. 3, a detail, is an alternative form, 35 showing inside elevation, a plain, ungrooved rod with a stop thereon, secured in vertical position by a collar above and one below, and

Fig. 4, a detail, is an alternative form, 40 showing inside elevation, a plain, ungrooved rod with an integral stop and sleeve to space the stops.

Referring now to the drawings; G is the 45 gear rack fixed to the piston-rod P, for reciprocating the piston. A projection g, on the rack G extends toward the stop rod R far enough to strike when the rack is raised against any one of the stops S, when set in contact or using position like the lowest one shown.

The rod R which is fixed in position, has a circumferential groove r, under each of the stops S, and a pin s, thru the stop S, lies in this groove and holds the stop in

vertical position on the rod, while allowing 55 it to rotate thereon.

Under each stop S are two recesses r¹ in which a steel ball s¹ seats under pressure of the spring s². One recess is so placed as to keep the stop in position when aligned 60 for contact with the projection g, and the other to keep it in position when set to keep it from being engaged by said projection. A handle s³ is provided for convenience in adjusting the stops by rotation. 65

The stop is drilled on its front or projecting end parallel with the rod R, and threaded to receive a set screw s⁴, and the head is cross-drilled with holes s⁵ to receive a sealing wire s⁶. At a convenient 70 adjacent place toward the front of the stop is drilled a hole s⁷. When the screw s⁴ has been so adjusted as to ensure its contact with the projection g just at the point where the desired quantity of liquid will 75 have been pumped the wire s⁶ is passed thru the hole s⁷ in the block and the parallel hole s⁵ in the screw head, drawn snug and sealed by the seal s⁸ in the usual manner.

Considering now Fig. 3, the rod R is 80 without groove, and the stop S is held in position by the collars C, C¹ and the pins c, c¹. Otherwise the mechanism is the same as shown in Figs. 1 and 2.

Figure 4, has a rod R without groove also 85 but the stops S, are extended forming a sleeve s⁹ above or below or both above and below the stop proper so that the stops rest one upon the other or may have an intervening washer (not shown). When 90 formed as shown in Fig. 4 the combined stop and sleeve units must completely cover the rod or be so held at the top or bottom or both as to prevent their longitudinal movement on the rod.

The stops may bear numbers as shown to indicate the gallons or other units of measure the pump is set to dispense, when said stop is brought into engaging position with the projection on the rack.

Obviously the ball might be replaced by a plunger pin with a rounded end to bear upon the rod, without departing from the spirit of my invention.

I claim as my invention and desire to secure by Letters Patent of the United States;

1. In combination with a projection on the piston rack of a measuring pump; a

2

quantity stop rod substantially parallel with said rack, stops on said rod adapted to be rotated thereon into and out of the path of said projection to limit the stroke of said means, a ball and spring within the stop for pressing said ball against the rod and recesses on the rod so placed as to permit the setting of stop so as to be either in or out of the path of said projection, and an adjustment screw on said stop substantially parallel with said rod, said screw and stop adapted to be sealed together to prevent rotation of the screw.

2. In combination with a projection on a reciprocable operating means of a measur-

ing pump; a quantity stop rod substantially parallel with said operating means, a stop rotatable on said rod, a ball within the stop and a spring within the stop, pressing said ball against the rod, and recesses on the rod so placed as to permit the setting of the stop at will so as to be either in or out of the path of said projection.

In testimony whereof I have hereunto set my hand in presence of two subscribing witnesses.

BENJAMIN F. GEYER.
